UNITED STATES PATENT OFFICE

2,229,586

CONE OR COP

Le Roy F. Ott, Providence, R. I., assignor to Standard Mill Supply Company, a corporation of Rhode Island

Application June 17, 1939, Serial No. 279,732

2 Claims. (Cl. 242—120)

This invention relates to a cone or cop upon which yarn is packaged for various uses and has for one of its objects to provide a covering upon such cone or cop which will be so protected at 5 its ends that the covering will not chip, roughen or break away.

Another object of this invention is to provide from the material of the body of the cop or cone a protection for the covering to prevent chipping or abrading of its ends.

A further object of the invention is to provide a protecting portion for a covering as a separate piece for positioning after the covering is applied in order that the covering may be more 15 easily and better performed.

With these and other objects in view, the invention consists of certain novel features of construction, as will be more fully described, and particularly pointed out in the appended claims.

20 In the accompanying drawing:

Fig. 1 is a side view of a cone or cop constructed in accordance with my invention.

Fig. 2 is a central section thereof.

25 Fig. 3 is a view similar to Fig. 2 but showing a modified arrangement.

Fig. 4 is a section on line 4—4 of Fig. 2.

Fig. 5 illustrates a section of a fragmentary end portion of the cone or cop with the tip removed.

30 Fig. 6 is a section view of the tip separated from the cone.

Heretofore in the manufacture and use of cones which have had wooden body cores covered with some material different than the body of the cone such, for instance, as cork or a composition of cork and rubber, the covering has been wound upon the body of the cone and cemented and the ends of the covering have been beveled but otherwise exposed so that in use where the cone 35 is subjected to some rough handling or tossing from one position to another, the ends become roughened to catch in the yarn or chipped and soon are in such condition that recovering is necessary. In order to provide a stronger cone 40 or cop I have arranged to recess the surfaces upon which the covering is applied but to leave protecting portions of the wooden body so that when the covering is inset into the recess the 45 ends or edges will be protected by a shoulder or flange on the cop or cone and thus prevent chipping or roughening of these end surfaces where the majority of the abrasion or chipping occurs,

50 and the following is a more detailed description 55 of the present embodiment of this invention, il-

lustrating the preferred means by which these advantageous results may be accomplished:

With reference to the drawing, 10 designates the body portion or core of the cone or cop which is usually of wood, maple wood being one 5 wood which is frequently used, altho various different woods or other rigid material may serve this purpose. This body core has the usual bore 11 reduced at its tip end as at 12 and enlarged at its base end as at 13 and chamfered as at 14, all of usual structure. The outer surface of 10 the body core is grooved as at 15 and recessed as at 16 to provide shoulders 17 and 18 by leaving flanges 19 and 20.

The composition covering consisting of a sheet 15 of cork or cork and rubber or other suitable sheet material 21 is wrapped about the body core in the recess 16 with its meeting edges abutting and is of a thickness so that its outer surface 22 will be substantially flush with the outer surfaces 23 and 24 of the flanges 19 and 20, or in some cases the covering may be slightly above the outer surfaces of the flange such, for instance, as 1/1000" or 2/1000 of an inch, the covering being compressible to approximately this 20 extent. The ends 25 and 26 of the sheet covering 25 closely abut and contact the shoulders 17 and 18 of the flange and are protected by the flange from chipping or roughening as these flanges are of harder and more rugged material 30 and will withstand the abuse which could not be withstood by the softer covering material.

In some cases instead of the flange 20 being integral with the body 10 a tip 30 may be provided as a separate unit, which tip has a central 35 portion 31 to extend into a reduced bore 32, with the head 33 of the tip extending outwardly, and the shoulder 34 contacting the end 35 of the body so as to form a shoulder for the protection of the edge 26 of the covering 21 as 40 will be readily apparent from Figs. 3, 5 and 6.

While I have described specific materials it will be readily apparent that other materials may be employed or the invention be made in one or several pieces as occasion dictates.

45 The foregoing description is directed solely towards the construction illustrated, but I desire it to be understood that I reserve the privilege of resorting to all the mechanical changes to which the device is susceptible, the invention 50 being defined and limited only by the terms of the appended claims.

I claim:

1. A yarn package cop comprising a wooden body core having an outer surface uniformly ta- 55

- pered throughout its length, a covering of cork composition about said outer surface terminating short of the axial extent of said body core, and flanges extending outwardly from said body at the ends of said covering and terminating at the outer surface of said covering to extend flush with the outer surface of the cork covering and continuing the taper of said body and protecting the opposite edges of said covering.
- 5 10 2. A yarn package cop comprising a body core having an outer surface uniformly tapered

throughout its length, a covering of cork composition about said outer surface terminating short of the axial extent of said body core, and flanges extending outwardly from said body at the ends of said covering and terminating at the outer surface of said covering and continuing the taper of said body to extend flush with the outer surface of the cork covering and protecting the opposite edges of said covering.

10
